PORTABLE TELEVISION RECEIVER CABINET

Albert J. Fitzgerald, Syracuse, N.Y., assignor to General Electric Company, a corporation of New York

Application December 4, 1956, Serial No. 44,067.

Term of patent 14 years

(Cl. D56—4)

FIG.1.

FIG.2.

FIG.3.

Fig. 1 is a perspective view of a portable television receiver cabinet showing my new design;

Fig. 2 is a plan view of a portion of the surface of the cabinet illustrated in Fig. 1; and

Fig. 3 is a cross sectional view of the portion of the surface of the cabinet shown in Fig. 2.

The woven material partially shown in Figure 1 is understood to be continuous over the entire surface of the sides, top and bottom of the cabinet.

The side not shown is the same in appearance as the side shown, and the back of the cabinet is unornamented.

I claim:

The ornamental design for a portable television receiver cabinet, as shown and described.
